CONVEYING DEVICE

Henry S. Marmorstein, Jersey City, N. J., and
 Robert A. Neuschotz, New York, N. Y.; said
 Neuschotz assignor to said Marmorstein

Application November 16, 1933, Serial No. 698,254

21 Claims. (Cl. 198—16)

This invention relates to conveying devices, such as escalators, package conveyors and the like devices.

An object of this invention is to provide an escalator or conveyor having means for automatically starting to operate when a person approaches or mounts the same or an object is deposited thereon.

Another object of this invention is to provide an escalator or conveyor of the character described, having means for automatically stopping at a predetermined period after starting to operate should no persons step thereon or objects be deposited thereon during said period, the construction being such that the period of operation is extended, if during said period another person mounts thereon or another object is deposited thereon.

A further object of this invention is to provide an escalator having photo-electric cell means for starting the operation thereof.

A still further object of this invention is to provide a conveyor of the character described having means for starting the operation of the conveyor automatically upon depositing an object thereon and for stopping the operation of said conveyor when the object moves off the conveyor.

A still further object of this invention is to provide a compact and strong conveying device of the character described, which shall comprise comparatively few and simple parts, be smooth and positive in operation, comparatively inexpensive to manufacture and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is an elevational, cross-sectional view of an escalator embodying the invention;

Fig. 2 is an enlarged, elevational, cross-sectional view of the switch device operated by a person approaching the escalator;

Fig. 3 is a wiring diagram, illustrating the electrical system for operating the structure shown in Fig. 1;

Fig. 4 is a partially diagrammatic view, illus-

trating a portion of an escalator caused to move by a person standing on any step of the escalator;

Fig. 5 is an elevational, cross-sectional view of the step shown in Fig. 4;

Fig. 6 is a cross-sectional view taken on line 5—6 of Fig. 5;

Fig. 7 is a diagrammatic view illustrating an electrical system similar to that shown in Fig. 3, but operated by photo-electric cells;

Fig. 8 is a rear elevational view of the top of the escalator;

Fig. 9 is a side, elevational, partially diagrammatic view of a belt conveyor for articles provided with automatic starting and stopping means embodying the invention;

Fig. 10 is a view similar to Fig. 9, but illustrating a modified construction;

Fig. 11 is a top plan view of a part of the structure shown in Fig. 10 with parts in cross-section; and

Fig. 12 is a side elevational view of the structure shown in Fig. 11.

Referring now in detail to the drawings, 10 designates an escalator embodying the invention, and may comprise an escalator of usual construction provided with accessories, described in detail hereinafter.

The escalator construction may comprise the usual motor 11 adapted to drive through gearing 12 a belt 13. The belt 13 is adapted to drive a 30 sprocket wheel 14 mounted on axle 15 below the upper landing or floor 15. Mounted below the lower landing or floor 16 is an axle 17 on which there is mounted the sprocket wheel 18. Interconnecting the sprocket wheels are the steps 20 mounted 35 on the usual chain 21, and each having a pair of rollers 22 and 23 coating with guides 24 and 25, respectively, in the usual manner.

As is well known in the art, the outer rollers 23 engage the sprocket wheels 14 and 18 for causing 40 movement of the series of steps. The steps are maintained in proper levels by means of the guides 24 and 25 cooperating with the rollers 22 and 23. This construction is well known in the art.

On opposite sides of the steps are provided the railing housings 27 and 28 having the usual inner belts 29 adapted to move around pulleys in the usual manner when the escalator is moving, said belts 29 serving as a hand grasp for the passengers on the escalator.

Means is provided for starting the operation of the escalator automatically when a person approaches the escalator so that the escalator need not continue running continuously without pas-

15

sengers. To this end, the railings 27 and 28 are extended beyond the top and bottom of the escalator. The railing is further provided with outer belts 30, similar to the belts 29 but operated by 5 a separate removable motor and being marked with transverse stripes 31. Thus, even though the escalator is at a standstill, the belts 30 may be caused to move to indicate to passengers that the escalator is set for operation, and the direction of such operation.

10 Mounted between the rails 27 and 28 on the lower level 16 is a switch 33 comprising a pair of floor members 34 and 35 hinged together, as at 15 36, and mounted on rubber blocks 37 supported on a bracket 38, fixed below the floor. The ends of the hinged members 34, 35 may be interconnected to the lower level floor 16 by means of plates 39, or in any other suitable manner. Disposed below said members 34 and 35 and fixed 20 within the floor is a box 40 on which there is mounted a bracket 41 having a terminal 42. There is also mounted on the bracket 42 and insulated therefrom, a member 44, to which there is hinged a lever 45 provided with a terminal 46 25 adapted to contact the terminal 42. A small coil tension spring 47 serves to normally retain the terminals 42 and 46 out of contact. A screw 49 is screwed to the lever 45 and contacts the underside of the member 34.

30 When a person approaching the escalator steps on either of the members 34 or 35, the lever 45 is rotated for bringing the terminals 42 and 46 into contact. A wire 50 is attached to the bracket 41 by means of a binding post, and a wire 51 is 35 interconnected to the member 41 by a binding post. The wire 50 is thus electrically connected to the terminal 42, whereas the wire 51 is electrically connected through the member 41 and lever 45 to the terminal 46.

40 Very slight movement of the members 34 and 35 is necessary for operating the switch 45. The rubber blocks 37 normally maintain the members 34 and 35 slightly lifted at the center merely sufficiently to open the gap between the terminals 42 and 46. The switch 45 forms part of the electrical system illustrated in Fig. 3 of the drawings.

45 A switch 33a similar to switch 33 shown in Fig. 2 is mounted on the upper level or floor 15, between the rails 27 and 28 so that a person transported upwardly on the escalator and stepping off the escalator, operates the top switch by stepping thereon. When the escalator is set for transporting persons down, a person on the floor 15 approaching the escalator will step on the switch 33a at the top and start movement of the escalator in the manner hereinafter explained.

50 Referring now to Fig. 3 of the drawings, 11 designates the motor, and numeral 54 designates a double throw double blade knife switch mounted on the usual panel board. The switch 54 is adapted to cooperate with a pair of lower terminals 56 and 57 and also with a pair of upper terminals 58 and 59. The terminal 56 is interconnected to the terminal 59 by a conductor 60. The terminal 57 is interconnected to the motor field by wire 57a. The terminal 59 is interconnected to the motor field by the wire 59a, and the terminal 58 is interconnected to the motor field by wire 58a. The wires 57a, 59a and 58a 55 form the three wire system for the field of the reversible motor 11, the wire 59a being the central wire of the three wire system. The switch 54 is provided with blades 54a and 54b and may be moved upwardly to contact the terminals 56, 70 57. The blade 54b is interconnected by wire 62

5 to one of the line feed wires 63. The other blade 54a is connected by wire 64 to a fixed terminal 65. A second fixed terminal 66, complementary to the terminal 65 is connected by wire 67 to the other feed line wire 68.

10 Fig. 3 also shows, diagrammatically, the manually actuated switches 33, 33a at the bottom and top of the escalator. The wire 51 interconnects the bottom lever 45 to a fixed terminal 52. A complementary spaced, fixed terminal 52a is connected by wire 51a to the top lever 45. The wire 50 interconnects the terminal 42 of switch 33 to the terminal 42 of switch 33a.

15 There is further provided, adjacent the top and bottom of the escalator, a pair of similar switches 70. Each comprises a bracket 71 on which there is slidably mounted a plunger 72 having a conductor head 73 and adapted to be retracted by means of a coil compression spring 74. The head 73 is adapted to interconnect fixed 20 terminals 75 and 76 at one end of wires 77 and 78. The wires 77 and 78 extend from the bottom of the escalator to the top and are provided with the terminals 75 and 76 at the opposite ends thereof. The circuit through said wires may be 25 closed by means of the conductor head 73 of the plunger 72 at either the top or bottom switch 70.

30 Normally, the plungers 72 are maintained out of contact with respect to the terminals 75 and 76, but may be moved into switch closing position 35 by pressing the plunger to compress the spring 74. For maintaining the plunger in switch closing position, there is provided a bell crank 80 having a hook 81 adapted to engage the head 73 when the plunger is moved to switch closing position. 35 For releasing the plunger there is provided a spring pressed rod 82 adapted to rotate the bell crank 80. Thus when the hook 81 is in engagement with the head 73 to hold the same in switch closing position, pressure on the rod 82 will cause 40 rotation of the bell crank 80 and disengage the hook 81 from the head 73, thus permitting the spring 74 to retract the plunger 72. The circuit through the wires 77 and 78 may thus be closed and opened either from the top or bottom of the 45 escalator.

45 The wire 78 is connected, as at 78a, to the feed line wire 68. The wire 77 is connected by wire 86, as at 87, to the other line feed wire 63. The wire 50 interconnecting the terminals 42, is connected by wire 88 to the line feed wire 63. The relay 85 is adapted to actuate a switch 90 connected by wire 91 to the feed line wire 68. Said switch 90 is adapted to engage a fixed contact 94 connected by wire 95 to a relay 96 operating a 55 quick closing and slow opening time switch 97 of any suitable well known construction. The relay 96 is interconnected by wire 99 to a switch arm 99a adapted to move into contact with either terminal 52 or 52a. The time switch 97 60 is adapted to close the terminals 65, 66.

55 The operation of the device will now be described. The double throw switch 54 is first moved either up or down, depending upon which direction it is desired to operate the escalator. Let us assume that for moving the escalator up the switch 54 is moved upwardly to engage the terminals 58 and 59. The switch arm 99a is also moved into contact with terminal 52. Thereafter one of the switches 70 must be actuated to set the circuit for operation. Upon pressing the plunger 72, shown on the left of Fig. 3, the circuit through the relay 85 will be closed, the current passing from the line wire 68 to the wire 78, 75

to wire 77, to wire 84, through relay 85, through wire 86, to the other line feed wire 63.

When the relay 85 is closed, the switch 90 is moved downwardly for engaging the fixed contact 94. The escalator does not yet start to operate. However, should a person approaching the escalator from the bottom, step on switch 33 located at the lower level 16, the terminals 42 and 46 will contact. The current will then pass through the relay 96 of the time switch 97. The current passes from the line feed wire 68 to the wire 91, through the switch 90, through the wire 95, through the relay 96, through wire 99, switch arm 99a, to wire 51, then through the wire 50 and wire 88 to the other feed line wire 63. When the relay 96 is energized, the time switch closes quickly, thus closing the gap between the two fixed terminals 65 and 66. The current then passes through the motor to start operation of the same. The current passes through the line feed wire 68, then through terminals 65, 66, through wire 64, blade 54a, terminal 58, wire 58a, to the motor field. The current passes from the field through wire 59a, through terminal 59, through blade 54b, and wire 62, to the other feed line wire 63.

The time switch 97 opens after a predetermined time. When the person steps off the escalator, he again steps on the upper switch 33a but this switch is cut out because switch arm 99a has been moved into contact with terminal 52. The predetermined period is preferably longer than is required for a person to travel from the bottom to the top of the escalator. Thus, when a person steps on the escalator, the escalator starts to operate and continues operating, until the time switch 97 opens and breaks the current through the motor to stop the escalator. If during said predetermined period another person approaches the escalator, the time switch will again move to full closing position, and the predetermined period of operation is extended. Thus, when no persons are using the escalator, the escalator remains inoperative. The escalator, furthermore, starts to operate automatically when a person approaches the escalator to use the same, and continues in operation for a time after the person has left the escalator to eliminate short stops of the escalator.

If the escalator is set for upward movement, the motor for operating the belts 30 is turned on and the belts 30 move continually upwardly to indicate to the passengers that the escalator is set for moving upwardly, and said belts 30 continue to move even when the escalator stops. If it is desired to set the escalator for downward movement, the motor for operating the belts 30 is reversed. The switch 54 is moved downwardly, the switch arm 99a moved into contact with terminal 52a, and one of the switches 70 closed. Should a person step on the upper switch 33a the current through the time switch is again closed. The current in the field of the motor, however, is reversed, since the current passes from the line feed wire 68 through wire 67, through the terminals 65, 66, through wire 64, through blade 54a, through terminal 56 and conductor 60, to terminal 59 and wire 59a. The current then passes from the field through wire 57a, to terminal 57, blade 54b, wire 62 to the line feed wire 63. The switch members 70 should be located in a position from which the operator of said switches may observe the entire escalator.

The floor switches 33, 33a may be located at any suitable distance from the top and bottom of the

escalator to permit sufficient time to elapse for overcoming inertia so that the escalator acquires full speed before the person stepping on the switch members actually reaches the first exposed step of the escalator.

In Fig. 7 there is shown a construction similar to that disclosed in Figs. 1 and 3 except that instead of the structure shown in Fig. 2 there is substituted a photo-electric cell switch device. In accordance with Fig. 7 there is mounted in the side rails 27 and 28 at the bottom and top of the escalator, boxes 100 and 101. Thus at the bottom of the escalator on both sides of the rail there is mounted a box 100 in the rail 27 and box 101 in rail 28, as indicated in Fig. 8 of the drawings. Within box 101 is a lamp 102 connected to a suitable source of electric current, the rays of said lamp passing through a small opening 103 in the box 101 and passing through an opening 104 in the box 100.

Within the box 100 there is mounted a photo-electric cell 105 of usual construction, connected to an amplifying circuit 106 of any suitable design, the current from the amplifying circuit being adapted to energize a relay 107. The relay 107 when energized, maintains a switch 108 out of contact with respect to a fixed contact 109. The fixed contact 109 is connected to the wire 50. The switch arm 108 is connected to the wire 51. The wires 50 and 51 may be connected to the relay 96 for the time switch 97 and to the feed line wire 63 in the manner shown in Fig. 3 of the drawings. Thus, normally when the light passes to the opening 104, the motor does not operate. However, should a person approaching the escalator, pass between the boxes 100 and 101 the passage of light to the photo-electric cell is momentarily interrupted, the relay is de-energized, the switch 108 drops into contact with the fixed contact 109, and the circuit for the time switch is closed for closing the motor circuit.

In Figs. 4, 5 and 6 there is shown a modified construction wherein the switches 33, 33a are replaced by switches mounted directly on the steps of the escalator. In accordance with the structure shown in Figs. 4, 5 and 6, there is suitably mounted alongside the escalator and preferably within the rails, a pair of elongated conductors 115 and 116 constituting third and fourth rails.

Each step in the escalator is provided with a hinged cover member 117. Pivoted to the underside of each step is a lever 118 to which there is screwed a screw 119 extending through an opening 120 in the top wall of the step. A coil compression spring 122 serves to press the screw 119 against the underside of the hinged member 117 for maintaining the same in slightly lifted position. The lever 118 is provided with a pair of spaced rollers 123 and 124 interconnected by a conductor 125. In normal position, the roller 124 contacts the third rail 115, but the roller 123 is out of contact with the fourth rail 116. Should a person step on any step, the hinged cover 117 of said step will press down on the screw 119 for causing pivotal movement of the lever 118 in a clockwise direction, looking at Fig. 5 of the drawings. The roller 123 will then be moved into contact with the fourth rail 116, bridging the circuit through said rails. The third rail 115 is connected to the wire 77. The wire 78 is connected to the feed line wire 68.

For the electrical system shown in Fig. 4, there is also provided a double throw double blade switch 130 having blades 131 and 132. Said blades are adapted when the switch is pushed up-

wardly, to engage a pair of fixed terminals 134 and 135. When the switch is swung downwardly, the blades 131 and 132 are adapted to contact a pair of fixed contacts 136 and 137. The terminal 5 or fixed contact 136 is interconnected by a conductor 136a to the terminal or fixed contact 135. The field of the motor is connected by a central wire 140 to the terminal 136. When the wire 141 from the field is connected to 10 the terminal 137 the third wire 142 extending from the field is connected to the terminal 134. The blade 132 is connected by wire 143 to the feed line 63. The operation of the system shown in Fig. 4 will now be described.

15 The switch 130 is first swung upwardly and one of switches 70 closed. Should anyone thereafter step on any step of the escalator, the circuit through the third and fourth rails is closed. The fourth rail 116 is interconnected to the blade 20 131 through a wire 116a. The motor then begins to operate since the current passes from the feed line 68 to the wire 98, then to wire 71, then to the third rail 115, through the conductor 125, to the fourth rail 116, through wire 116a, to the blade 25 131, then to terminal 134, then through wire 142 to the field. From the field the current passes through the central wire 140, to terminal 136, conductor 136a, terminal 135, blade 132, to the wire 143, to the feed line 63. To reverse the 30 direction of the motor the switch 130 is merely swung downwardly for reversing the direction of the current through the field.

In Fig. 9 there is shown a conveyor of the belt type for transporting packages, boxes, etc. The 35 belt 150 is shown as passing around a pair of pulleys 151, 152. The pulley 152 is connected by a belt 153 to a pulley 154, the latter being connected through suitable gearing 155 to an operating motor 156. Means is provided for operating the 40 motor 156 automatically upon pushing a package onto the top of the belt conveyor 150. To this end, there is hinged to a platform 157 a leaf 158. A package or box may be pushed from the platform 157 onto the inclined leaf 158 from whence 45 it will slide onto the belt. Pivoted to the platform 157 is a lever 160 pressed by a spring 161. A screw 162 screwed to the end of the lever contacts the underside of the leaf 158, the spring 162 serving to maintain the screw in contact with 50 said leaf.

Attached to the underside of platform 157 is a 55 fixed terminal 164, and fixed to the outer end of the lever 160 is a complementary terminal 165 normally maintained out of contact with respect 55 to the terminal 164 by the spring 161.

It will now be noted that when a package is pushed onto the leaf 158 the leaf will swing downwardly for rotating the lever 160 in a counter-clockwise direction to bring the terminal 165 into 60 contact with the terminal 164.

There is further provided a switch 70a similar to the switch 70 described above. The head of the plunger portion of said switch is adapted to bridge the gap between the pair of fixed contacts 65 170 and 171. The contact 170 is connected directly to the current of the feed line wires 172, by wire 174 to the terminal 165 on the lever 160. The fixed contact 171 is connected by wire 175 to a relay 176 adapted to actuate a quick closing 70 and slow opening time switch 177. The relay 176 is in turn connected by wire 178 to the other terminal 164. The time switch 177 is adapted to close the gap between a pair of fixed contacts 180 and 181. The fixed contact 181 is connected directly to the wire 175, whereas the fixed contact 75

180 is connected by wire 183 to the motor. The motor is further connected by wire 184 to the feed line wire 173.

The operation of the device shown in Fig. 9 will now be described. The switch 70a is first 5 closed to bridge the gap between the contacts 178, 171. Thereafter, should a package be shoved onto the leaf 158, the terminal 165 will be swung into contact with the terminal 164. This action 10 will close the circuit through the relay 176 for 10 actuating the time switch, the current passing from line 173 to wire 174, through the contacts 165, 164, through wire 178, to the relay; thence to wire 175, through the contacts 171, 170, to the other line wire 172. The time switch closes 15 quickly and thus closes the circuit through the motor. The motor circuit is closed for a pre-determined period after which the time switch opens and breaks the motor circuit. Of course, the period during which the time switch is closed 20 is regulated so as to be greater than that required for transporting the package the full length of the conveyor.

In Figs. 10, 11 and 12 there is shown a modified construction, in accordance with which pushing 25 a package onto the conveyor automatically starts the conveyor, and passage of the package off the conveyor automatically stops the action of the conveyor if no other packages are being conveyed.

Referring now to Figs. 10, 11 and 12 of the 30 drawings, the same disclose a belt 190 passing over a pair of rollers or pulleys 191 and 192. The roller 192 is driven by means of a belt 194 received on pulley 195 driven by motor 196 connected thereto by suitable gearing. The roller 35 192 is provided for the purpose hereinafter appearing, with a pair of spaced, metal, peripheral rings 197 and 198.

There is further provided on the shaft for said roller 192, a pair of slip rings 197a and 198a contacting brushes 199 and 200. The brush 199 is connected by wire 201 to the field of motor 196, said field in turn being connected to the feed line 202. The other brush 200 is connected directly to the other feed wire 203. The belt 190 is 45 provided on the inner surface thereof with two spaced, endless flexible metallic strips 205 and 206. The strips 205 and 206 are attached to the belt by any suitable rivets and contact the rings 197 and 198, respectively, continuously. Incorporated 50 into the belt 190 are two pairs of concentric coil springs 207 and 208, extending entirely around the belt. Each pair of coil concentric springs are adapted to be normally out of contact with each other when no article is deposited on the belt. However, when an article is deposited on the belt, the concentric coil springs 55 contact one another. The outer coil spring 208 of each pair of concentric springs is connected by wire 209 to the inner coil spring 207 of the other pair. The outer coil springs 208 are further connected by wires 210 and 211 to the metal strips 205 and 206, respectively. The metal rings 197 and 198 are furthermore connected by wires 212 and 213 to the slip rings 197a and 198a, respectively. 65

The operation of the device will now be described. Normally the belt is at rest, no current passing through the motor by reason of the outer coil springs 208 being out of contact with respect 70 to the inner coil springs 207. However, should any package be deposited on the belt, the spring 208 at some part of the belt will contact an adjacent portion of the inner spring 207 and complete the circuit through the motor. The circuit pass- 75

ing from the feed line 203 to the brush 200, to slip ring 198a, through wire 213, to ring 198, to flexible metal strip 206, through wire 211, to outer coil 208, of one pair of concentric springs, to inner coil 207 of said pair of springs, through wire 209, to the outer coil 208 of the other pair of concentric springs, then through wire 210 to the flexible metal strip 205, then to ring 197, then through wire 212, to slip ring 197a, to brush 199, to wire 201, to the field of the motor 196, and then to feed line wire 202. It will be noted that the current through the motor will be maintained as long as any packages are on the belt and any portion of the outer coil springs contacts their respective inner coil springs. However, when no packages are on the belt, the current through the motor is broken and the operation of the belt ceases.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawings is to be interpreted as illustrative and not in a limiting sense.

Having thus described our invention, we claim as new and desire to secure by Letters Patent:

1. In combination, a conveying device, means controlled by the object to be conveyed for automatically starting the operation of said device either in one direction or the other, including means for selectively setting said device for operation in one of said directions only, and means including a single time switch for automatically stopping the operation of said device in either direction after a predetermined period of operation.

2. In combination, a conveying device, means controlled by the object to be conveyed for automatically starting the operation of said device either in one direction or the other, including means for selectively setting said device for movement in one of said directions only, means for automatically stopping the operation of said device after a predetermined period of operation, and means for automatically extending said period of operation.

3. In combination, an escalator movable in opposite directions, and means controlled by a person approaching the escalator to mount the same for automatically starting the operation of said escalator in one direction, and belt means alongside the escalator belts for indicating the direction the escalator will move upon being started.

4. In combination, an escalator, a pair of switches on the floors adjacent the upper and lower ends of the escalator and adapted to be stepped upon by persons approaching the escalator for using the same, a reversible motor for operating said escalator in the up or down direction, means for setting the motor to operate the escalator in one or the other of said directions, and means for automatically starting the motor for operating the escalator in the direction for which it is set for a predetermined period when a person approaching the escalator in said direction, steps on the switch at the adjacent end of the escalator.

5. In combination, a conveyer, reversible means capable of moving said conveyor in opposite directions, means for selectively setting said first means to move the conveyor in one direction only,

when operation of said means is started, and means to automatically start operation of said conveyor by said first means in the direction for which the same is set, by an object approaching the conveyor in said direction.

6. In combination, a conveyor, reversible means for moving said conveyor in opposite directions, means for selectively setting said first means to move the conveyor in one direction only when operation of said means is started, and means to automatically start operation of said conveyor by said first means in the direction for which the same is set, by an object approaching the conveyor in said direction, and moving means for indicating the direction for which the conveyor is set to move.

7. In combination, an escalator, a motor adapted for operating said escalator in opposite directions, means for selectively setting the motor for actuating the escalator for movement in one of said directions, and means controlled by a person approaching the escalator in said direction to mount the same, for automatically starting operation of the escalator by said motor in the direction for which it is set.

8. In combination, an escalator, a motor adapted for operating said escalator in opposite directions, means for selectively setting the motor for actuating the escalator for movement in one of said directions, means controlled by a person approaching the escalator in said direction to mount the same for automatically starting operation of the escalator in the direction for which it is set, and moving means for indicating the direction for which the escalator is set to move.

9. In combination, an escalator, a motor adapted for operating said escalator in opposite directions, means for selectively setting the motor for actuating the escalator for movement in one of said directions only, means controlled by a person approaching the escalator in said direction to mount the same for automatically starting operation of the escalator in the direction for which it is set, and a member disposed alongside the escalator having marks thereon, and means for moving said member in the direction for which the escalator is set to move, for indicating said direction.

10. In combination, an escalator, a pair of switches on the floors adjacent the upper and lower ends of the escalator, adapted to be stepped upon by persons approaching the escalator for using the same, a motor for operating the escalator, a circuit for said motor including a quick closing and slow opening time switch, a circuit for said time switch, and means for throwing either one of said pair of switches into said last circuit and cutting the other of said pair of switches out of said circuit.

11. In combination, an escalator, a pair of switches on the floors adjacent the upper and lower ends of the escalator, adapted to be stepped upon by persons approaching the escalator for using the same, a motor for operating the escalator, a circuit for said motor including a quick closing and slow opening time switch, a circuit for said time switch, and means for throwing either one of said pair of switches into said last circuit and cutting the other of said pair of switches out of said circuit, said last circuit including a relay switch, a circuit for the coil of said relay switch, and switches adjacent the upper and lower ends of the escalator for controlling said relay coil circuit.

12. In combination, an escalator, a pair of

switches on the floors adjacent the upper and lower ends of the escalator, adapted to be stepped upon by persons approaching the escalator for using the same, a reversible motor for operating said escalator in the up or down direction, a circuit for said motor including means for reversing said motor, a quick closing and slow opening time switch interposed in said circuit, a circuit for operating said time switch, means for throwing either one of said pair of switches into said last circuit, and cutting the other of said pair of switches out of said last circuit.

13. In combination, an escalator, a pair of switches on the floors adjacent the upper and lower ends of the escalator, adapted to be stepped upon by persons approaching the escalator for using the same, a reversible motor for operating said escalator in the up or down direction, a circuit for said motor including means for reversing said motor, a quick closing and slow opening time switch interposed in said circuit, a circuit for operating said time switch, means for selectively throwing one of said pair of switches into said last circuit and cutting the other of said pair of switches out of said last circuit, another switch interposed in said last circuit, a relay for actuating said last switch, a circuit for the coil of said relay, and means for closing the relay coil circuit from either the upper or lower ends of the escalator.

14. In combination, an escalator, a pair of switches on the floors adjacent the upper and lower ends of the escalator and adapted to be stepped upon by persons approaching the escalator for using the same, a reversible motor for operating said escalator in the up or down direction, means for setting the motor to operate the escalator in one or the other of said directions, and means including a single time switch for automatically starting the motor and operating the escalator in the direction for which it is set for a predetermined period when a person approaching the escalator in said direction, steps on the switch at the adjacent end of the escalator, and means for rendering inoperative the switch at the other end of the escalator.

15. In combination, a conveyor, reversible means for moving said conveyor in opposite directions, means for selectively setting said first means to move the conveyor in one direction only when operation of said means is started, and means to automatically start operation of said conveyor by said first means in the direction for which the same is set, by an object approaching the conveyor in said direction, and moving means for indicating the direction for which the conveyor is set to move, said means comprising a belt having markings thereon movable alongside the escalator belt and means for selectively moving said marked belt in opposite directions.

16. In combination, a conveyor, reversible means capable of moving said conveyor in oppo-

site directions, means for selectively setting said first means to move the conveyor in one direction only, when operation of said means is started, and means to automatically start operation of said conveyor by said first means in the direction for which the same is set, by an object approaching the conveyor in said direction, and means including a single time switch for automatically stopping operation of said escalator in either direction after a predetermined period of operation.

17. In combination, a conveying device, photo-electric cell means controlled by the object to be conveyed for automatically starting the operation of said device either in one direction or the other, including means for selectively setting said device for operation in one of said directions only, and means including a single time switch for automatically stopping the operation of said device in either direction after a predetermined period of operation.

18. In combination, a conveying device, means controlled by the object to be conveyed for automatically starting the operation of said device either in one direction or the other, including means for selectively setting said device for movement in one of said directions only, photo-electric cell means for automatically stopping the operation of said device after a predetermined period of operation, and means for automatically extending said period of operation.

19. In combination, a conveyor, reversible means capable of moving said conveyor in opposite directions, means for selectively setting said first means to move the conveyor in one direction only, when operation of said means is started, and photo-electric cell means to automatically start operation of said conveyor by said first means in the direction for which the same is set, by an object approaching the conveyor in said direction.

20. In combination, a conveyor, reversible means for moving said conveyor in opposite directions, means for selectively setting said first means to move the conveyor in one direction only, when operation of said means is started, and photo-electric cell means to automatically start operation of said conveyor by said first means in the direction for which the same is set, by an object approaching the conveyor in said direction, and moving means for indicating the direction for which the conveyor is set to move.

21. In combination, an escalator, a motor adapted for operating said escalator in opposite directions, means for selectively setting the motor for actuating the escalator for movement in one of said directions, and photo-electric cell means controlled by a person approaching the escalator in said direction to mount the same, for automatically starting operation of the escalator by said motor in the direction for which it is set.
